UNITED STATES PATENT OFFICE.

ARTHUR STANWORTH, OF DETROIT, MICHIGAN.

TOOL HOLDER.

Application filed August 30, 1922. Serial No. 585,129.

To all whom it may concern:

Be it known that I, ARTHUR STANWORTH, a British subject, residing at Detroit, county of Wayne, State of Michigan, have invented 5 a certain new and useful Improvement in Tool Holders, and declare the following to be a full, clear, and exact description of the same, such as will enable others skilled in the art to which it pertains to make 10 and use the same, reference being had to the accompanying drawings, which form a part of this specification.

My invention relates to tool holders shown in the accompanying drawings and 15 more particularly described in the following specification and claim.

The primary object of the present invention is to provide a tool holder of simple 20 and inexpensive construction in which a positive driving relation is obtained between the tool and the holder.

A further object of the invention is to provide for material reduction in the cost 25 of tools manufactured of "high speed" steel now upon the market by forming the tool with a relatively short slightly tapering shank, ground and fitted to the tool socket to insure accuracy of operation; the holder being constructed with interlocking means 30 adapted to engage the shank of the tool to provide a positive driving connection between the tool and holder.

A further object of the invention is to provide for the rapid interlocking of the 35 tool in the holder and for releasing the same therefrom as required.

A further object of the invention is to provide a device adapted to receive and support different tools as for example drills, 40 reamers, counterbores, spot-facers or the like as required.

A further object is to provide a holder fitted with positive driving means equally effective for either metal or wood working 45 tools and in carrying these objects into effect the tool holder is fitted with a driving pin having an enlarged head projecting from a counterbore in the wall of the holder into a longitudinal peripheral groove 50 in the tapering shank of the tool, thus insuring a positive driving connection between the tool and holder in which the danger of shearing the driving pin is reduced to the minimum. To provide for 55 the removal of the tool from the holder the latter is constructed with a transverse

tapering hole adjacent the end of the tool shank when lodged therein so that upon inserting a properly constructed pin adapted to bear upon the end of the tool shank the 60 tool may be forced from the holder.

Having now indicated in a general way the object and purpose of my invention I will proceed to a more detailed description 65 of the same:

In the drawings accompanying this specification,

Figure 1 is a side elevation of the holder with a "drill" inserted therein.

Figure 2 is a side elevation partly in section of the holder showing a "reamer" engaged therein.

Figure 3 is a cross-sectional view taken on or about line 3—3 of Figure 2.

Referring now to the letters of reference 75 placed upon the drawings:

A, denotes a tool having a relatively short slightly tapering shank A', fitted to the tapering socket B', of the tool holder B,

C, is a driving pin having an enlarged 80 head C' projecting into the tool socket from a perforation B², which is enlarged at its ends to form inner and outer shoulders B⁴ and B⁵, respectively, adjacent the ends of the perforation.

The shank C², of the driving pin is slightly tapered and when driven into the wall of the holder from the inside of the socket its outer end is riveted as at C³, against the shoulder B⁵ that it may be rigidly secured to the holder;—the outer end of the perforation is then filled with solder D, covering the riveted end of the pin flush with the outer surface of the holder.

Extending from the end A² of the tool 95 shank toward the cutting end of the latter is a longitudinal peripheral groove A³, to receive the enlarged head C' of the driving pin;—a positive driving relation is thus obtained between the tool and holder upon 100 inserting the tool shank in the socket of the latter.

B³ is a tapering perforation extending 105 transversely through the wall forming the socket of the holder, to receive a tapering pin (not shown) designed when driven into the perforation to bear upon the arched end of the tool shank whereby the tool may be released from the holder. The transverse tapering perforation and the tapering pin 110 inserted therein are so constructed in relation to each other that the pin cannot be

driven completely through the holder—which might result in the latter being lost—the pin however is adapted to bear upon the arched top of the tool shank and thus 5 release the tool from the socket of the holder.

As indicated in dotted lines in Figures 2-3 the perforation for the driving pin C may be bored through the wall of the holder from the opposite side;—the pin C may 10 then be inserted through the wall into its seat in the counterbored end of the perforation opposite thereto, the “open” perforation through which it was inserted may then be closed with solder.

15 It will be apparent that a great variety of tools with a relatively short shank ground to fit the socket of the holder may be interchangeably employed therewith;—the cost of the tools being materially reduced 20 through the use of a short shank.

Having thus described my invention what I claim is:

In a device of the character described, a tool holder provided with a socket, the wall 25 of which has a perforation enlarged at its inner and outer ends to form an inner and

an outer shoulder adjacent the ends of the perforation, a tool having a shank fitted in the socket of the holder provided with a longitudinal groove extending from the end 30 of the shank, and a pin inserted in the perforation from within the socket and having an enlarged head at its inner end fitting the enlarged inner portion of the perforation with the outer side of the head bearing 35 against the inner shoulder of the perforation to prevent the pin from working exteriorly through the wall of the socket and at its inner side projecting into the groove of the shank of the tool to provide 40 a driving connection between the tool and holder, the outer end of the pin being riveted against the outer shoulder of the perforation to hold the pin against displacement inwardly of the socket. 45

In testimony whereof I sign this specification in the presence of two witnesses.

ARTHUR STANWORTH.

Witnesses:

L. G. THOMAS,
PATRICK J. MURPHY.
